UNITED STATES PATENT OFFICE

2,030,608

QUILTING FRAME

Earle E. Pike, Corsicana, Tex.

Application December 11, 1934, Serial No. 757,041

6 Claims. (Cl. 112—119)

My invention relates to quilting frames, and has particular reference to an improved adjustable frame adapted to support the quilting materials and finished quilt during the stitching or quilting operation.

It is an object of my invention to provide a quilting frame having a series of spaced, longitudinally-extending rollers, certain of which are adapted to support the materials from which a quilt is to be made and one of which is adapted to receive and support the finished quilt, and to associate with such rollers, means for feeding and winding the materials and for retaining an appreciable length of the materials in a taut, stretched condition between the rollers, whereby the exposed materials may be readily stitched together to form the finished quilt.

It is an object of my invention to provide a quilting frame having a series of material-feeding and quilt-receiving rollers rotatably mounted in suitable end frames, and to so mount the roller-supporting end frames that said frames and the rollers may be readily adjusted to balance the rollers as the quilting materials are initially placed on the feed rollers, and as the materials are fed from the feed rollers and accumulate upon the receiving roller, this adjustment or "balancing" being desirable in order to maintain the stretched materials in a horizontal position during the stitching or quilting operation.

It is an object of my invention to provide a quilting frame having a series of spaced material-feeding and quilt-receiving rollers, and to suspend these rollers from an overhead support whereby the materials contained between the feed and receiving rollers may be readily moved transversely and longitudinally before the operator, in the case of hand sewing, or transversely and longitudinally beneath the stitching mechanism of a sewing machine, in the case of machine sewing, suitable means being provided for adjusting the rollers vertically with respect to the operator or sewing mechanism of a sewing machine.

It is a further object of my invention to provide a support for the rollers and materials which is shaped to permit the stitching to be extended to the extreme marginal edges of the materials without interference between the support and stitching mechanism of the sewing machine, and which will permit the rollers and materials to be moved endwise from beneath the stitching mechanism without contact between the support and stitching mechanism.

It is a still further object of my invention to provide a quilting frame which is collapsible, and which may be folded to form a relatively compact device for shipping and/or storing purposes, and to so construct the quilting frame that it is readily adjustable, cheap and easy to manufacture,

strong and durable and highly efficient in the purposes for which designed.

In the accompanying drawing wherein I have illustrated the preferred embodiment of my invention,

Figure 1 is a view in elevation of my improved quilting frame, showing the same suspended from a suitable overhead support by means of which the quilting materials may be passed transversely and longitudinally beneath the stitching mechanism of a sewing machine.

Fig. 2 is a sectional view on the line 2—2 of Fig. 1.

Fig. 3 is an enlarged, fragmentary, side elevation of one of the roller supporting side frames 15 and the arcuate supporting arm for suspending said side frame from its overhead support,

Fig. 4 is an enlarged fragmentary plan view of one end of the material-feeding and quilt supporting rollers and the associated side frame, 20 this view being taken on the line 4—4 of Fig. 3, and,

Fig. 5 is an enlarged sectional view on the line 5—5 of Fig. 1.

Referring to the drawing, wherein like reference characters have been employed to designate like parts throughout the several views, the numeral 1 designates a suitable overhead wire, cable or rod extending between the spaced supports 2 and 3 which may be the opposite walls 30 of a room or shop, this wire, cable or rod being attached to said supports by means of adjustable brackets 4, whereby the tension upon the wire, cable or rod 1 constitutes the overhead track or 35 trolley by means of which the quilting frame is supported.

My quilting frame comprises a main horizontal beam 5 of metal, wood or other suitable material, slightly greater in length than the overall width 40 of the quilt to be made on the quilting frame, this beam and the parts supported therefrom being suspended from the overhead wire, cable or rod 1 by means of supporting arms 6 and 7, the lower ends of which are pivotally connected to the beam 45 5 near the opposite ends thereof. These supporting arms 6 and 7 may be of metal, wood or other suitable material and are pivotally attached to the main horizontal beam 5 by means of angled plates 8 and 9 riveted or otherwise secured to 50 the lower ends of the supporting arms 6 and 7 and to beam 5. Each supporting arm 6 and 7 carries at its upper end a grooved trolley wheel 10 journaled on a bolt 11 which may be inserted within any one of a series of apertures 12 provided near the upper end of each arm. The angular position of the supporting arms 6 and 7 55 with respect to the main horizontal beam 5 determines the vertical position of the quilting frame with respect to the supporting wire, cable or rod 60

1, and to maintain the desired angular adjustment of the arms and, hence, the relative distance between the beam 5 and wire, cable or rod 1, I provide arms 13 and 14 having their lower ends 5 pivotally connected to the beam 5 and their upper ends passing through clamps 15 attached to the arms 6 and 7 near the upper ends thereof, these clamps being forced into frictional contact with the arms 13 and 14 by means of clamping bolts 10 16. For shipping and storing purposes, the arms 6 and 7 and 13 and 14 may be folded to assume a position parallel to the main beam 5 as shown in dotted lines in Fig. 1, the arms 6 and 7 resting on the upper surface of the beam 5 and the arms 15 13 and 14 lying adjacent one side face of said beam.

Attached to each end portion of the main beam 5 is an arcuate arm 17, the upper end 18 of which extends at right angles to the remainder of the 20 arm and is bolted, riveted or otherwise secured to the rear face of the beam 5, it being noted that the arcuate arms 17 are disposed transversely of the beam 5. The lower end of each arm 17 is pivotally connected to the mid portion of a 25 side frame 19 whose intermediate portion is substantially straight and whose end portions are curved upwardly as best shown in Figs. 3 and 5. In order to permit relative angular adjustment between the arms 17 and the side frame members 30 19, I provide a series of apertures 20 throughout the lower portion of each arm 17 and associate with each frame member 19 a hook 21, the upper free end of which is adapted to enter one of the 35 series of apertures 20 to retain the desired angular relation between the arms 17 and side frame members 19. Extending between the side frame members 19 are two material-feeding rollers 22 and 23 and a quilt-receiving roller 24, each having end trunnions journaled in spaced apertures 40 in the opposed side frame members 19. The end or ends of each of the rollers 22, 23 and 24 are provided with ratchets 25, 26 and 27 respectively, having pivoted locking dogs or pawls 28, 29 and 33 which coact with the respective ratchets to 45 lock the rollers against rotation. In the accompanying drawing, I have shown a portion of the stitching mechanism of a sewing machine 31 in order to illustrate and describe the use of my improved quilting frame when operated to permit the machine stitching or sewing of a quilt.

Having thus described the construction of my improved quilting frame, I will now refer to the use of such frame when utilized in the manufacture of a quilt. Assuring that the overhead wire, cable or rod 1 has been suspended between the 55 opposed supports 2 and 3 and stretched to the desired degree of tautness by means of the adjustable brackets 4, the supporting arms 6 and 7 of the quilting frame are moved upwardly about their pivotal mountings until they assume a position such as shown in Fig. 1. The arms 13 and 14 are then inserted beneath the clamps 15 and the clamping bolts 16 tightened, whereby the frictional engagement between the clamps 15 and 60 arms 13 and 14 maintains the desired angular adjustment between the beam 5 and the supporting arms 6 and 7. The bolts 11 carrying the grooved trolley wheels 10 are then inserted in corresponding apertures 12 at the upper ends of 65 the supporting arms 6 and 7 and the entire quilting frame is lifted to a position where the trolley wheels 10 will overlie and ride upon the wire, cable or rod.

The rollers 22 and 23 are then removed from 70 the side frame members 19 by releasing the pivot-

ed locking dogs 28 and 29 from engagement with the ratchets 25 and 26 and springing the said frame members outwardly to disengage the roller trunnions from the apertures in the side frame members. The marginal edge of a sheet of suitable base fabric, usually of plain color, is tacked or otherwise secured at spaced points along the length of the roller 22. A sheet of filling material, usually cotton batting or the like, is superimposed upon the base fabric sheet and the fabric 10 and filling materials are carefully and tightly rolled upon the roller 22. The marginal edge of a length of suitable top fabric, usually ornamental or decorative in design, is tacked or otherwise secured at spaced points along the length of 15 the roller 23 and this top fabric is then carefully and tightly rolled upon the roller 23. The rollers 22 and 23 are then placed between the side frame member 19 with the base fabric and filling material passing beneath the roller 23. The outer 20 free edges of the base fabric, filling material, and top fabric are then brought together, pulled across the space between the rollers 22 and 23 and the quilt-receiving roller 24, and tacked or otherwise secured at spaced points along the length of the 25 roller 24. The locking dogs or pawls 28, 29 and 30 are then brought into engagement with their respective ratchets 25, 26 and 27 and the rollers are thus locked against further rotation, it being understood that the locking dogs and ratchets 30 maintain the superimposed materials in a tight, stretched condition.

It will be noted that when the quilting materials are initially mounted on the rollers preparatory to the stitching or quilting operation, the bulk 35 of weight is at the rear of the quilting frame. Hence it will be necessary, in order to obtain the desired horizontal positioning of the superimposed fabric extending between the roller 23 and the quilt-receiving roller 24, to remove the 40 hook members 21 at opposite sides of the frame from engagement with the apertures 20 and to swing the rear ends of the side frames 19 upwardly about their pivotal connection with the lower ends of the arcuate arms 17 until the materials between 45 the rollers 23 and 24 assume the desired horizontal position and the frame is properly balanced, whereupon the hooks 21 are again engaged within appropriate apertures 20 in the arms 17 to maintain this position until further adjustment becomes necessary.

Assuming that the height of the beam 5 and the parts suspended therefrom has been properly adjusted with respect to the platform or table underlying the stitching mechanism of the sewing machine 31, the entire quilting frame is moved endwise beneath the stitching mechanism, the arcuate shape of the arms 17 permitting this movement and preventing contact between the said arms and stitching mechanism. The operator then moves the entire frame back and forth beneath the stitching mechanism to effect the stitching or quilting of the materials, this stitching or quilting usually extending in spaced, parallel lines, transversely of the materials, although the free suspension of the materials and the ability of my frame to be moved from side to side and from front to rear permits the material to be stitched or quilted in designs other than the straight transverse stitching. As soon as the 70 length of materials extending between the rollers 23 and 24 has been stitched or quilted, the operator releases the locking dogs or pawls 28, 29 and 30 from their respective ratchets and rolls up the stitched materials onto the roller 24, this roll- 75

ing operation unwinding another length of base, filling and top materials from the rollers 22 and 23 and placing the same in proper stretched condition and position between the rollers 23 and 24. 5 After the stitching or quilting has progressed to a point where the bulk of weight is located at the front end of the frame, due to the transfer of the materials from the rollers 22 and 23 to the quilt-receiving roller 24, the length of materials extending between the rollers 23 and 24 no longer maintains the desired horizontal position, i. e., the frame becomes unbalanced, and it becomes necessary to elevate the forward ends of the side frame members 19, which can be readily accomplished by disengaging the hooks 21 from the apertures 20, swinging the forward end of the frame upwardly about the pivotal connections with the lower ends of the arcuate arms 17, and replacing the hooks 21 in appropriate apertures 20 in the arms 17. The stitching or quilting operation continues until the length of materials wound upon the rollers 22 and 23 becomes exhausted, whereupon the tacks are removed from the inner ends of the materials on the rollers 22 and 23 and the entire lengths of materials are wound upon the roller 24. The roller 24 is then removed from between the side frames 19 and the stitched or quilted materials are unwound from the roller 24, cut into suitable lengths, and passed 30 to a suitable stitching machine where an edge binding is sewed over the marginal edges of the laminated sheet to form a finished quilt.

While I have elected to illustrate and describe my improved quilting frame used in connection with a sewing machine, it is to be understood that the frame is not limited to machine sewing but is highly efficient when used in connection with hand sewing, the entire frame and the materials carried thereon being readily movable back and forth and from front to rear of the operator. It is to be further understood that the form of my invention herein shown and described is to be taken as a preferred embodiment of the same, and that various changes may be made in the shape, size and construction of parts without departing from the spirit of my invention or the scope of the subjoined claims.

What I claim as new and desire to secure by Letters Patent is:—

50 1. A quilting apparatus comprising a main horizontal beam, spaced material-feeding and quilt-receiving rollers suspended from said beam, a horizontal track above said beam, arms pivotally attached at their lower ends to said beam and angularly adjustable with respect thereto, means at the upper ends of said arms for engaging the horizontal track, and means for retaining said arms in any one of a plurality of angular positions with respect to the beam to determine the vertical distance between the horizontal track and said beam.

2. A quilting apparatus comprising a main horizontal beam, spaced material-feeding and quilt-receiving rollers suspended from said beam, a horizontal track above said beam, a supporting arm pivotally attached at its lower end to said beam and angularly adjustable with respect thereto, a trolley wheel at the upper end of said supporting arm for engaging the horizontal track, a second arm pivotally attached at its lower end to said beam with its free upper end crossing said supporting arm, and means engaging the supporting arm and said second arm to retain said supporting arm in any one of a plurality of angular positions with respect to said beam to de-

termine the vertical distance between the horizontal track and said beam.

3. A quilting apparatus comprising a main horizontal beam; spaced material-feeding and quilt-receiving rollers suspended from said beam; a horizontal track above said beam; a supporting arm pivotally attached at its lower end to said beam and angularly adjustable with respect thereto; means at the upper end of said supporting arm for engaging the horizontal track; an arm pivotally attached at its lower end to said beam adjacent the lower end of the supporting arm with the free upper ends of the two arms crossing; and an adjustable clamp carried by one of the arms and engaging the other arm to retain the supporting arm in any one of a plurality of angular positions with respect to said beam to determine the vertical distance between the horizontal track and said beam.

4. A quilting apparatus comprising a main horizontal beam; spaced material-feeding and quilt-receiving rollers suspended from said beam; a horizontal track above said beam; a pair of supporting arms pivotally attached at their lower ends to said beam and angularly adjustable with respect thereto; means at the upper ends of said supporting arms for engaging the horizontal track; a second pair of arms each pivotally attached at its lower end to said beam adjacent the lower end of each of the first mentioned arms with the free upper ends of the adjacent supporting and second-mentioned arms crossing; and an adjustable clamp carried by each of the supporting arms and frictionally engaging the adjacent second-mentioned arm to retain each supporting arm in any one of a plurality of angular positions with respect to said beam to determine the vertical distance between the horizontal track and said beam.

5. A quilting apparatus comprising a main horizontal beam, spaced material-feeding and quilt-receiving rollers suspended from said beam, a horizontal track above said beam, supporting arms pivotally attached at their lower ends to said beam and angularly adjustable with respect thereto, means at the upper ends of said supporting arms for engaging the horizontal track, arms pivotally attached at their lower ends to said beam adjacent the lower ends of each of the supporting arms with their free upper ends crossing said supporting arms, and means engaging the supporting and second mentioned arms to retain said supporting arms in any one of a plurality of angular positions with respect to said beam to determine the vertical distance between the horizontal track and said beam, the supporting and second mentioned arms being movable to assume positions parallel to said beam when the frame is removed from the horizontal track.

6. A quilting apparatus comprising a main horizontal beam; a horizontal supporting track above said beam; means for suspending said beam from said horizontal track; spaced arms depending from said beam and provided with a plurality of spaced apertures; side frame members pivotally attached to said arms; spaced material-feeding and quilt-receiving rollers journaled between said side frame members; and hooks carried by said side frame members, the free ends of said hooks being adapted to enter any of the spaced apertures in the arms to secure said side frame members in any one of a plurality of angular positions with respect to said arms.
